UNITED STATES PATENT OFFICE.

CHARLES NORTH, OF COLORADO SPRINGS, COLORADO.

BOX-CAR DOOR.

1,072,638.

Specification of Letters Patent. Patented Sept. 9, 1913.

Application filed June 24, 1912. Serial No. 705,608.

To all whom it may concern:

Be it known that I, CHARLES NORTH, a citizen of the United States, residing at Colorado Springs, in the county of El Paso and State of Colorado, have invented certain new and useful Improvements in Box-Car Doors; and I do declare the following to be a full, clear, and exact description of the invention, such as will enable others skilled in the art to which it appertains to make and use the same.

This invention relates to improvements in car doors, and particularly to doors for box or grain cars.

One object of the invention is to provide a door of this character formed in a plurality of independently movable sections and having an improved means for fastening said sections in operative position to form a positively grain-tight closure for the door opening of the car.

A further object is to provide an improved construction and arrangement of relief door whereby the grain or other contents of the car may be removed without opening the main door.

With these and other objects in view, the invention consists of certain novel features of construction, and the combination and arrangement of parts as will be more fully described and claimed.

In the accompanying drawings: Figure 1 is an outer side view of a portion of one side of a car having my improved door applied thereto and showing the door in closed position; Fig. 2 is a vertical cross sectional view on the line 2—2 of Fig. 1; Fig. 3 is a similar view showing the door in open position; Fig. 4 is a vertical longitudinal sectional view of a portion of the side of a car showing the door in closed position, and illustrating the relief door in position to discharge the grain from the car; Fig. 5 is a similar view with the door in open position; Fig. 6 is a horizontal section taken on the line 6—6 of Fig. 1.

Referring more particularly to the drawings, 1 denotes the wall of the box car to which the invention is applied, and 2 denotes the door frame around an opening in the side of the car. On the inner side of the car and spaced a suitable distance from the side wall thereof is a casing 3, between which and the wall of the car is slidably mounted my improved door.

The door is constructed of two or more

horizontally slideable members, and is here shown as consisting of a lower member 4 and an upper member 5, said members being of sufficient width to extend from the bottom to near the top of the car. The lower member 4 is preferably somewhat wider than the upper member, and when said members are in closed position the upper member 5 rests on and has a grain tight engagement with the lower member 4. When, however, the members 4 and 5 of the door are slipped back into the casing 3 to an open position, the upper member 5 is separated from the lower member 4 by a horizontally disposed supporting rail 6 which is arranged in the casing immediately above the lower member of the door and is designed to support the upper member, thereby permitting the lower member to be readily shifted to an open or closed position without disturbing the upper member. In order to facilitate the engagement of the upper member of the door with the rail 6 when said upper member is shifted to an open position and to permit said upper member to drop down into grain tight engagement with the upper edge of the lower member when said upper member is shifted to a closed position, the outer end of the plate 6 is beveled or inclined on its upper surface, as shown at 7, and the lower edge of the upper member 5 of the door is also beveled, as shown at 8. By providing the parts with the beveled surfaces 7 and 8, it will be seen that when the upper member of the door is shifted to a full closed position the beveled surface 8 of the door member will come into engagement with the beveled surface 7 on the end of the rail 6, thus causing said door member to drop or slide downwardly into engagement with the upper edge of the lower door member. It will also be seen that as soon as the upper member is started back on its opening movement, that the engagement of the beveled surfaces 7 and 8 will lift and guide the upper member of the door back on the rail 6.

In order to prevent the outer ends of the door members from rising when in closed or operative position, I provide the outer edges of said members with notches 9 which are engaged with stop pins or bolts 10 connecting the side of the car and the adjacent portion of the casing 3 near the edge of the door opening with which the free ends of the door members are engaged, said pins or

bolts when thus engaged by the notches 9 effectually holding the door members against rising when in a closed position and also forming stops which limit the 5 movement of the door members in this direction. The opposite or inner edge of the upper door member 5 is also held against casual upward movement by a stud or stop pin 11 in the inner edge of one wing hereinafter described.

The door fastening mechanism comprises a pair of locking wings or bars 12, one of which is connected to each side of the door frame 2 by hinges 2', said wings being 15 adapted to swing inwardly to bring their free edges into engagement with the outer sides of the door members 4 and 5 when the latter are in closed position, and said wings or bars are of such width that when swung 20 inwardly in operative position they will firmly clamp the door members into grain tight engagement with their casing on the inner side of the car. In order to hold the wings 12 in closed position and to positively 25 prevent the door members 4 and 5 from jarring or slipping back in their casing, I provide locking bolts 13 which are secured to the outer sides of the wings and are adapted to be shifted into engagement with 30 suitable keepers 14 in the outer sides of the door members 4 and 5, as shown. Hence the pressure of the grain in the car which is outward against the door members 4 and 5 bears them against the wings and is resisted 35 by the hinges 2' so long as the wings remain in the position shown in Fig. 2, and the engagement of the bolts 13 with the keepers 14 holds the wings in this position so that the bolts themselves do not take the strain 40 of the grain. The stud or stop pin 11 in the left-hand wing passes over the upper edge of the upper member 5 as this wing is turned into position, as seen in dotted lines in Fig. 1, and said stud therefore prevents 45 this member from rising. So long as it cannot rise, the engagement of the beveled surfaces 7 and 8 prevents it from moving to the left, and therefore this position of the left wing while maintained will prevent the 50 opening of the upper door member. The wings 12 are preferably provided with suitable knobs or handles 12', whereby they may be readily operated.

In the lower member 4 of the door a slight 55 distance above the floor of the car is a grain discharging opening 15 through which the grain or contents of the car may be removed without opening the door. The opening 15 is provided with a relief door in the shape 60 of a plate 16 which lies against the outer side of the door member 4. When the door member 4 is in a closed position the plate 16 is held in sliding engagement therewith by recesses 16' in the inner edges of the wings 12 and it may be raised in said recesses and

held in an elevated position to uncover the opening 15 by means of a chain 17 or other suitable form of supporting element which is connected to the top of the door frame or some other suitable support, and is provided on its lower end with a hook 18 adapted to be engaged with an eye or opening 19 in the plate 16, as shown.

In opening a door as thus constructed, the relief door or plate 16 is first raised in the recesses 16' in the inner sides of the wings, and the uncovering of the opening 15 relieves the pressure bearing against the inside of the main door. When this pressure has been reduced, the bolts 13 are retracted and the wings 12 swung outward to the position seen in Fig. 3. This carries the stop pin 11 away from the top of the door section 5, and the latter may then be raised and slid aside over the track 6, after which the bulk of the grain within the car can be unloaded in the usual manner. Finally when the grain is nearly all gone, the lower door section 4 is slid aside in the ordinary way. Meanwhile the relief door 16 can hang from the cord as shown, or may be entirely removed so as to be out of the way.

A car door constructed and arranged as herein shown and described will form a positively grain tight closure for the door opening in the car, and said door may be quickly and easily shifted to closed and open position and securely fastened in closed position. It will also be noted that my improved door may be readily applied to any form of box car already constructed or in course of construction.

From the above description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as described and claimed.

Having thus described my invention, what I claim is:

1. In a grain car door, the combination with the car wall having an opening surrounded by a frame, a casing at one side of the opening, a horizontal track fixed between said wall and casing and beveled at its inner end, upright wings hinged to the side bars of said frame, a stop pin carried by one of said wings, and bolts on the inner edges of the wings; of the door made in upper and lower members whereof the lowermost has a relief opening and the uppermost is movably disposed upon the lowermost and has a beveled corner adapted to ride over the beveled end of said track, the width of said members being such that they are engaged by said wings when the 130

latter are swung inward, said wings having recesses in their inner edges, a relief door movably mounted in said recesses over the outer face of the lower main door member, and keepers on both door members adapted to be engaged by said bolts, for the purpose set forth.

2. In a grain car door, the combination with the car wall having an opening surrounded by a frame, the casing at one side of the opening, a horizontal track fixed between said wall and casing, upright wings hinged to the side bars of said frame, and bolts on the inner edges of the wings; of the door made in upper and lower members whereof the lowermost has a relief opening and the uppermost is movably disposed upon the lowermost and adapted to ride over said track, the width of said members being such that they are engaged by said wings when the latter are swung inward, said wings having recesses in their inner edges, a relief door movably mounted in said recesses over the outer face of the lower main door member, and keepers on both door members adapted to be engaged by said bolts, for the purpose set forth.

3. In a grain car door, the combination with the car wall having an opening surrounded by a frame, the casing at one side of the opening, a horizontal track fixed between said wall and casing and beveled at its inner end, upright wings hinged to the side bars of said frame, a stop pin carried by one of said wings, and bolts on the

inner edges of the wings; of the door made in upper and lower members whereof the uppermost is movably disposed upon the lowermost and has a beveled corner adapted to ride over the beveled end of said track, the width of said members being such that they are engaged by said wings when the latter are swung inward, and keepers on both door members adapted to be engaged by said bolts, for the purpose set forth.

4. In a grain car door, the combination with the car wall having an opening surrounded by a frame, the casing at one side of the opening, a horizontal track fixed between said wall and casing and beveled at its inner end, upright wings hinged to the side bars of said frame, and bolts on the inner edges of the wings; of the door made in upper and lower members whereof the uppermost is movably disposed upon the lowermost and adapted to ride over said track, the width of said members being such that they are engaged by said wings when the latter are swung inward, and keepers on both door members adapted to be engaged by said bolts, for the purpose set forth.

In testimony whereof I have hereunto set my hand in presence of two subscribing witnesses.

CHARLES NORTH.
